Primary Examiner — Kelley Donnelly*(74) Attorney, Agent, or Firm* — Boyle Fredrickson, S.C.(57) **CLAIM**

The ornamental design for a tool bin, as shown and described.

DESCRIPTION

FIG. 1 is an isometric view of a preferred embodiment of a tool bin in accordance with the present invention;

FIG. 2 is a front elevation view of the tool bin of FIG. 1;

FIG. 3 is a back elevation view of the tool bin of FIG. 1;

FIG. 4 is a first side elevation view of the tool bin of FIG. 1;

1;

FIG. 6 is a top view of the tool bin of FIG. 1; and,

FIG. 7 is a bottom view of the tool bin of FIG. 1.

The broken lines shown in the drawings are for illustrative purposes only and form no part of the claimed design.
